Attorney

UNITED STATES PATENT OFFICE

RUSSELL E. TUPPER, OF SALEM, MASSACHUSETTS

RAILWAY PAD

Application filed December 11, 1928. Serial No. 325,192.

My invention relates to improvements in railway pads, and has for its purposes to provide a wear resisting protection pad and cushion intended for use between railway ties and rails, or railway ties and tie plates, switches, frogs or the like; to provide a pad capable of furnishing protection to the tie from moisture and weather conditions, eliminating the cutting and rupture; to insure a minimum wear of railway ties in use; to minimize the noise and rattle of ties, tie plates and railway tracks; to increase the normal life of railway tracks and rolling stock used upon the same; and to provide the various other advantages and results made evident from the following specification.

I accomplish the objects of my invention by coating that side (hereinafter called the under side) of a suitable elastic pad (preferably of asbestos) intended for use against the railroad tie, with a solution of adhesive waterproofing material (preferably creosote and pitch).

In use, the coating on the pad seals the pores or other openings in that portion of the tie beneath the pad, rendering it moisture proof and causing it to adhere to the pad, thus causing the pad to act as an effective roof and protection thereto. In wear, as the tie becomes compressed by the weight of the rail, and passing rolling stock thereon, so as to cause a settling of the surface, the pad, or roof so called, becomes increasingly effective in excluding moisture from the tie and avoiding resultant deterioration.

The various features of novelty embodied in my invention are hereinafter characterized and indicated, and particularly so in the appended claims, but for a full understanding of the invention, its objects and advantages, reference is made to the following detailed description, in connection with the accompanying drawings, in which like characters of reference refer to similar parts throughout the various views.

In the drawings Figure 1 shows an end view of my improved pad mounted between a railway tie and a railway plate with an end view of the rail surmounting same. Figure 2 shows a perspective view of the pad.

Referring again to Figure 1, A shows the railway tie, B shows the pad, B² shows the waterproof coating on the pad, C shows the tie plate. D shows the rail. E shows the spikes which hold the assembled parts in their relative position.

In Figure 2, F shows the holes provided for the spikes E.

While I have illustrated and described a preferred construction for carrying my invention into effect, this is capable of variation or modification without departing from the spirit of the invention. I therefore do not wish to be limited to the exact details of construction herein set forth but desire to avail myself of such variations and modifications as come within the scope of the appended claims.

It is, of course, evident that the use of the railway plate shown is merely optional.

Having thus described my invention I claim as new and desire to secure by Letters Patent of the United States of America:—

1. A pad for a rail of a railroad, or other part of a track, composed of asbestos and having its under side coated with a waterproof adhesive material.

2. A pad of asbestos, having its under side coated with a waterproof adhesive material, between a rail of a railroad or other part of a track and the supporting tie therefor.

3. A pad for a rail of a railroad, or other part of a track, composed of a durable cushion substance, having its under side coated with a waterproof adhesive material, between said part and a support therefor.

4. The combination with a railroad rail and its tie, of an intervening pad, having its under side coated with a waterproof adhe-

sive material, as and for the purposes specified.

5. As an improved article of manufacture, a pad for railway rails, comprising an elastic block with a flat undersurface coated with a waterproof adhesive material, substantially as and for the purposes specified.

6. The combination with a railroad rail, tie plate and tie, of an intervening pad, having its underside coated with a waterproof adhesive material, as and for the purposes stated.

In testimony whereof I affix my signature.
RUSSELL E. TUPPER.
